UNITED STATES PATENT OFFICE.

LIDO J. PATRICK, OF SAN DIEGO, CALIFORNIA.

MACHINE-GUN.

1,347,753.

Specification of Letters Patent. Patented July 27, 1920.

Application filed August 23, 1917. Serial No. 187,810.

To all whom it may concern:

Be it known that I, Lido J. PATRICK, a citizen of the United States, residing at San Diego, in the county of San Diego and State of California, have invented certain new and useful Improvements in Machine-Guns, of which the following is a specification.

My invention relates to machine guns, more particularly a several battery machine gun in which a series of barrels are arranged in a horizontal row and in which a large number of cartridges may be fired simultaneously, and the objects of my invention are: first, to provide such a gun in which the cartridges are loaded automatically from a cartridge magazine which may be replaced with other magazines of the same kind; second, to provide a machine gun of this class in which the firing breech consists of a cylinder with four cartridge receptacles spaced apart in the periphery thereof, the one for receiving the cartridge, one for firing, one for emptying, and the other for positioning the cylindrical firing breech; third, to provide a machine gun of this class in which the same is capable of a large radial movement both vertical and horizontal thus permitting the gun to be positioned for various ranges as desired; fourth, to provide a gun of this class which is light and capable of being handled and moved about easily by one man; fifth, to provide a machine gun of this class which may be readily placed in condition so that it is inoperative by the enemies; sixth, to provide a gun of this class which is simple and economical of construction, durable, easy to operate, and will not readily deteriorate or get out of order.

With these and other objects in view as will appear hereinafter, my invention consists of certain novel features of construction, combination, and arrangement of parts as will be hereinafter described in detail and particularly set forth in the appended claims, reference being had to the accompanying drawings and to the characters of reference thereon which form a part of this specification, in which:

Figure 1 is a top or plan view of my machine gun minus the shield 17; Fig. 2 is a side elevational view thereof, showing the tripod support thereof fragmentarily; Fig.

3 is a top view of a fragmentary portion of the gun with the magazine removed and showing the cartridge receptacles in position for receiving the cartridges ready to be fired; Fig. 4 is a sectional view through 4-4 of Fig. 2; Fig. 5 is a rear elevational view of the gun showing the tripod legs fragmentarily and showing a portion of the tripod in section to facilitate the illustration; Fig. 6 is a top view of one of the cartridge receptacles on an enlarged scale; Fig. 7 is a rear end elevational view thereof; Fig. 8 is a front end elevational view thereof; Fig. 9 is a detailed top view of the operating handle shown removed from the gun; Fig. 10 is a side elevational view of one of the barrels removed from the gun; and Fig. 11 is a fragmentary rear view of the breech revolving device showing by dotted lines the position when the quarter revolution is completed.

Similar characters of reference refer to similar parts throughout the several views of the drawings.

The tripod 1, bracket 2, bracket 3, supporting key 4, horizontal bar 5, horizontal bar 6, side member 7, side member 8, firing bar 9, firing member 10, breech revolving member 11, breech cylinder 12, breech cylinder control 13, handle 14, magazine 15, barrels 16, and shield 17 constitute the principal parts of my machine gun.

The tripod 1 consists of a cylindrical member to which are pivotally connected three leg members 1^a by means of lugs 1^b. Pivotally mounted centrally on the top of this cylindrical member 1 is a bifurcated bracket 2 by means of a pin 2^a and in said bracket is pivotally mounted a bracket 3 by means of a pin 3^a. This bracket 3 is provided in its upper surface with a slot 3^b for the insertion of the key 4 therein. This key 4 being slidably mounted in the slot 3^b permits slight shifting movement of the gun frame relatively to the tripod. This key 4 is supported on the frame by means of the loops 4^a mounted on the horizontal supports 5 and 6 near the middle of the frame. Secured to the ends of these supports 5 and 6 are the end members 7 and 8 which are provided with notches in their upper surface conforming to the magazine 15 which fits therein. The side member 7 is provided

with an extended handle member 7^a adapted to facilitate the support and positioning of the gun and is held by the operator in his left hand. This side member 7 is also provided with an upwardly extending portion 7^b adapted for a support for the spring 11^a which spring is for the purpose of holding the breech revolving member 11 in a non-engaging position normally and assists in throwing said member 11 back into position after the breech cylinders have been revolved to their firing position. These side members 7 and 8 are provided with forwardly extending members 7^c and 8^a to which is secured a horizontal bar 8^b which is adapted to assist in supporting the barrels 16 in their proper position. Each barrel 16 is supported in a barrel support 16^a which is provided with a downwardly extending lug 16^b as shown best in Fig. 10 of the drawings. The rear extended end of the barrel fits snugly in a hole in the bar 6 and the lug 16^b is secured against said bar 6, thus securing the barrel in position relatively to the bar 6. Mounted between the bar 6 and the bar 5^a are the revoluble breech cylinders 12 by means of pins 12^a in their opposite ends, which extend into holes in the bars 6 and 5^a. These revoluble breech cylinders are each provided with four equally spaced recesses 12^c in their outer surfaces, adapted for the cartridge to fit therein and these cylinders are positioned so that the cartridge on the one side is in alinement with the barrel, so that the cartridge in firing is on one side while in the recess on the opposite side there is provided a roller 13^a revolvably mounted on a spring 13 which is secured to a support 13^b which is secured to the horizontal bar 6. This roller 13^a engages the cartridge recess on one side, positioning the cartridge in the recess on the opposite side in alinement with the barrel in firing position, and the recess in the upper side receives the cartridge from the magazine and the discharged cartridge drops out of the cartridge recess on the lower side so that with each quarter revolution of the breech cylinder, one of the recesses receives the cartridge, in another the cartridge is fired, another discharges the cartridge and the other receives the roller 13^a for positioning said cylinder. Mounted in the horizontal bars 6 and 5^a are the bars 12^c upon which is secured the cartridge support 12^e which fits closely over the outer surface of the cylinder 12 and against the outer side of the cartridge when firing and holds the cartridge in position in the recess 60 in its revolution from the top side to where it is discharged. The back end of this cylinder is provided with four angular notches 12^d which are engaged by the lugs 11^b on the member 11, shown best in Fig. 3, so that when the member 11 is shifted endwise,

the cylinder is revolved one-fourth revolution, and when released, the spring 11^a thrusts the bar 11 back.

Mounted against the side 8 is a curved guide member 8^c upon which one end of the bar 11 rests and there is provided a spring 11^e secured to the bar 5^a, tending to hold the bar 11 up in the position shown best by solid lines in Fig. 11 of the drawings but when said member 11 is moved endwise and downwardly by hand pressure on the handle member 14 which handle member is secured to the bar 11^d which bar is secured to the bar 11 as shown best in Fig. 5, the one end of said bar 11 is guided by the curved guide member 8^c and its other end is depressed by its engagement with the spring 11^a and the spring 11^e is depressed and the bar assumes the position shown by dotted lines in Fig. 11 so that the lug 11^b engages the cylinder 12 85 in its movement.

Secured to the bar 5^a and extending over the member 11 are guides 11^d for the bar 11. Mounted between the side members 7 and 8 is a shaft 10^a upon which is pivotally mounted the firing member 10 which is provided with a torsion spring 10^b, tending to hold the member 10 against the firing bar 9 at all times. This firing member 10 is provided with a forwardly extending angular portion 10^c which is engaged by a lug 11^e mounted on a bar 11^d so that when said bar 11^d is shifted endwise and downwardly for revolving the cylinder 12, the trigger 10 is tipped away from the firing bar 9, and when it is released, the torsion spring 10^b thrusts said trigger against the bar 9 with sufficient force to thrust the firing pins 9^a supported in the bar 9 against the cartridge caps, thus discharging the cartridges. The magazine 105 is provided with a plurality of compartments, the lower side of which are hopper shaped for directing the cartridge in the proper position into the upper recess in the breech cylinder and each compartment is 110 provided with a spring actuated plunger 15^a, adapted to rest against the cartridges to facilitate their movement into position in the lower end of the compartment. This magazine is also provided with a plate 15^b 115 which is adapted to hold the cartridges in position when the magazine is not positioned on the gun but which is removed when the magazine is positioned properly on the gun to permit the cartridges to drop into the recess in the breech cylinder. The operating handle 14 is provided with a lug 14^a which is adapted to be inserted in a hole in the bar 11^d and drop down between the lug 11^e and the bar 11^a so that said operating handle 14 125 may be removed from the gun, thus rendering it inoperative when it is necessary to leave the gun or when it is liable to fall into the hands of the enemy. The magazine is secured to the gun frame by means of the 130

hooks 15° at each end. Mounted on the front portion of the frame and adapted to rest against the magazine is a shield or guard 17 which is provided with a hole 17° for the operator to look through for finding the range, and on the side of the gun, next to the handle 7°, are sights 16° and 7° for sighting purposes.

Though I have shown and described a particular construction, combination and arrangements of parts, I do not wish to be limited to this particular construction, combination, and arrangement but desire to include in the purview of my invention the construction, combination and arrangement substantially as set forth in the appended claims.

It is obvious that with this construction there is provided a machine gun in which there are several barrels arranged in a row and in which a plurality of cartridges may be fired simultaneously. That the bar 11 is moved endwise and downwardly on a curve by moving the handle 14 endwise and downwardly. That the key 4 and the handle 14 may be removed and taken along or destroyed thus making the gun practically useless for the enemy. That by reason of the pivotal movements of the brackets 2 and 3 and the pivotal movement of the bracket 2 in the cylindrical member 1, the gun may be moved to various positions. That the gun as a whole is very simple and economical of construction, capable of rapidly firing a large number of shots at a time and rapid repeating.

Having thus described my invention, what I claim as new and desired to secure by Letters Patent is:

1. A machine gun including, a series of barrels arranged in a horizontal row, a cartridge retainer revolvably mounted contiguous to the breech end of each of said barrels, a manually operated endwise and downwardly shiftable bar provided with a plurality of extending lugs for engaging said retainers in its movement for revolving said retainers simultaneously a one-quarter revolution and a magazine mounted over said cartridge retainer adapted to deliver cartridges to each of said retainers with each one-quarter revolution.

2. A machine gun including, a series of barrels arranged in a horizontal row, a cartridge retainer revolvably mounted contiguous to the breech end of each of said barrels, a manually operated endwise and downwardly shiftable bar provided with a plurality of extending lugs for engaging said retainers in its movement for revolving said retainers simultaneously a one-quarter revolution and a magazine mounted over said cartridge retainer adapted to deliver cartridges to each of said retainers with each one-quarter revolution, means for stopping

said cartridge retainer at a certain pre-determined point in its revolution so that a cartridge in said retainer stops in alinement with one of said barrels with each one-quarter revolution.

3. A machine gun including, a series of barrels arranged in a horizontal row, a cartridge retainer revolvably mounted contiguous to the breech end of each of said barrels, a manually operated endwise and downwardly shiftable bar provided with a plurality of extending lugs for engaging said retainers in its movement for revolving said retainers simultaneously a one-quarter revolution, a magazine mounted over said cartridge retainer adapted to deliver cartridges to each of said retainers with each one-quarter revolution, means for stopping said cartridge retainer at a certain pre-determined point in its revolution so that a cartridge in said retainer stops in alinement with one of said barrels with each one-quarter revolution and means resting against the side of said cartridge retainer adapted to engage the outer surface of said cartridge for supporting it when it is discharged.

4. A machine gun including, a series of barrels arranged in a horizontal row, a cartridge retainer revolvably mounted contiguous to the breech end of each of said barrels, a manually operated endwise and downwardly shiftable bar provided with a plurality of extending lugs for engaging said retainers in its movement for revolving said retainers simultaneously a one-quarter revolution, a magazine mounted over said cartridge retainer adapted to deliver cartridges to each of said retainers with each one-quarter revolution, means for stopping said cartridge retainer at a certain pre-determined point in its revolution so that the cartridge in said retainer stops in alinement with one of said barrels with each one-quarter revolution, means resting against the side of said cartridge retainer adapted to engage the outer surface of said cartridge for supporting it when it is discharged and a shield mounted in front of said magazine provided with a hole therein for sighting through.

5. In a machine gun, the combination of a series of barrels arranged in a horizontal row, a cartridge retainer revolvably mounted contiguous to the breech end of each of said barrels provided with a plurality of notches in its outer surface conforming to and adapted to receive a cartridge, means for engaging and revolving said cartridge retainers simultaneously, means for stopping said cartridge retainer at a certain predetermined point in its revolution so that a cartridge in said retainer stops in alinement with one of said barrels with each quarter revolution and a magazine mounted over said cartridge retainer with a separate compartment for

each retainer adapted to conduct a cartridge to each notch in said retainer in its revolution, and a shield mounted in front of said magazine provided with a hole therein for sighting through, and a firing bar in operative connection with the means for revolving said cartridge retainer for firing one of the

cartridges in each of said retainers after a part revolution and alinement of the cartridge with the barrel.

10

In testimony whereof, I have hereunto set my hand at San Diego, California, this 18th day of August, 1917.

LIDO J. PATRICK.
